AUTOMATIC HYDRAULIC ELEVATOR VALVE
CONTROL

Vincent F. Lovejoy, San Diego, Calif.

Application November 13, 1937, Serial No. 174,499

5 Claims. (Cl. 121—38)

My invention relates to an automatic hydraulic elevator valve control, and the objects of my invention are:

First, to provide a novel control for a hydraulic elevator valve which control is automatic in its operation;

Second, to provide a control for a hydraulic elevator valve which will automatically control the opening and the closing of said valve;

Third, to provide a control for a hydraulic elevator valve which will close said valve in such a way as to avoid the formation of a hydraulic hammer;

Fourth, to provide a control for a hydraulic elevator valve which control in cooperation with the hydraulic elevator valve, will automatically stop the elevator at any predetermined level of elevation regardless of the amount of the load being carried by said elevator;

Fifth, to provide a control of this class which avoids the use of springs and thereby complies with safety laws or ordinances regulating the use and operation of elevators;

Sixth, to provide a control of this class which will stop the elevator either in its descent or ascent upon failure of electric power;

Seventh, to provide a hydraulic control for a hydraulic elevator valve; and

Eighth, to provide on the whole a novelly constructed automatic hydraulic elevator valve control which is durable, efficient in its action, and which will not readily deteriorate or get out of order, all in proportion to its function.

With these and other objects in view as will appear hereinafter, my invention consists of certain novel features of construction, combination, and arrangement of parts and portions as will be hereinafter described in detail and particularly set forth in the appended claims, reference being had to the accompanying drawings and to the characters of reference thereon which form a part of this application in which:

Figure 1 is a sectional view taken along the line 1—1 of Fig. 6; Fig. 2 is a fragmentary view on a slightly enlarged scale over the scale of Fig. 1 with parts and portions broken away to facilitate the illustration and showing the cross head, the knuckle member, and the knuckle member trip member in detail; Fig. 3 is a fragmentary sectional view taken along the line 3—3 of Fig. 1 on an enlarged scale; Fig. 4 is a fragmentary sectional view taken through the line 4—4 of Fig. 2 and of the same scale as Fig. 2; Fig. 5 is a fragmentary sectional view taken along the line 5—5 of Fig. 2 and is of the same scale

as Fig. 2; Fig. 6 is a view taken along the line 6—6 of Fig. 1 and is of the same scale as Fig. 1; Fig. 7 is a fragmentary sectional view taken along the line 7—7 of Fig. 6 and is on an enlarged scale over the Fig. 6; Fig. 8 is a sectional view taken along the line 8—8 of Fig. 1 and is on an enlarged scale over the Fig. 1; and Fig. 9 is a diagrammatic illustration of my automatic hydraulic elevator valve control and shows in particular the principle of its operation.

Similar characters of reference refer to similar parts and portions throughout the several views of the drawings:

Cylinder 1, piston rod 2, crosshead 3, crosshead 15 guide 4, knuckle member 5, trip member 6, valve gate lever 7, mercury switch 8, mercury switch trip member 9, solenoids 10 and 11, solenoid plungers 12 and 13, valve 14, check valve 15, pressure relief valve 16, pump 17, electric motor 18, solenoid 19, connection panel 20 and casing 21 constitute the principal parts and portions of my novel automatic hydraulic elevator valve control.

For the elevator, which is not shown, to either 25 rise or descend, the gate member G of the valve A, indicated in Figs. 1 and 9 of the drawings, must be open. This valve member A is positioned between the cylinder of the hydraulic elevator and the pump for the hydraulic elevator. Neither 30 the cylinder nor the pump just mentioned are shown. The pipe P communicates with the cylinder for the hydraulic elevator. The gate G of valve A is shown closed in Fig. 1 of the drawings. This gate member G pivots about the journal B 35 in the body of the valve A. The gate G is either opened or closed by pivoting about the journal B by means of the valve gate lever 7 which lever is connected with said journal B. This lever 7 consists of the two arms 7a and 7b, 7a being shorter than 7b. The arm 7b carries the weight 40 7c which may be shifted along this arm 7b to any desired position and secured in that position by the bolt 7d. The arm 7a is secured by its end to the end 3b of the link 3a of the crosshead 45 3, the end 3b of link 3a being secured within slot 7e in the end of arm 7a. Hence as the crosshead 3 moves along its guide member 4, the gate G of the valve A in pivoting about its journal B is either opened or closed by the arm 50 7a of the gate lever 7.

The crosshead guide 4 is secured to one face of the channel member C as shown best in Figs. 1 and 3 of the drawings. This channel member C stands on one of its sides and is secured along one edge of the channel member D by means of

the bolt E, nut H, and sleeve member F as shown best in Figs. 3 and 6 of the drawings. The cross-head 3 has in its lower side a groove 3c extending therethrough to conform to the rail portion 4a of the crosshead guide 4. Thus the crosshead 3 will be retained on this guide member 4, yet it will be free to slide therealong. The crosshead 3 is connected to the piston rod 2; one end of the rod extends through the crosshead and is retained therein by means of the nuts 2b and 2c as indicated best in Figs. 1 and 3 of the drawings. To the opposite ends of the piston rod 2 is secured the piston 2a, which piston reciprocates within the cylinder 1. The cylinder 1 has the end cap members 1a and 1b. The piston rod 2 extends through the cap 1a, and the end of pipe 1d is secured in a concentric opening in the cap member 1b to admit fluid to or discharge fluid from the cylinder 1. These two cap members 1a and 1b are secured upon the ends of the cylinder 1 by means of the bolts 1c. Hydraulic fluid such as water is admitted to the cylinder 1 through the pipe 1d. The hydraulic fluid is drawn from the reservoir R through pipe 17d and pipe 17c into the centrifugal pump 17. This pump 17 is driven by an electric motor 18 through the shaft 18a, the flexible coupling member 18b, and shaft 17a. Hydraulic fluid is discharged from the pump 17 through pipe 17b and passes through the check valve 15 into the pipes 15a and 1d into the cylinder 1. This hydraulic fluid, as it is pumped into the cylinder 1, drives the piston 2a from the end of the cylinder 1 having the cap 1b to the end of the cylinder having the cap 1c. As the piston 2a is thus moved, the crosshead member 3 also moves in the same direction because of its connection to the piston rod 2, and as this crosshead member 3 moves as hereinbefore described, the gate G of the valve A is at the same time being opened because of the connection of the gate G with the arm 7a of the valve gate lever 7 and the link member 3a of the crosshead 3. The piston 2a in the cylinder 1 will be driven to the end of the cylinder 1 having the cap 1a as hydraulic fluid is pumped into the cylinder 1, and, upon reaching this end, will remain there until the valve 14 opens permitting the water within the cylinder 1 to flow back to the reservoir R through the pipe 1d, 14f, 14e and 17d. The valve 14 is controlled by the solenoid 11. The solenoid 11 has the plunger 13, which plunger is connected to the lever 14b of the valve 14 by means of the link 13a. This link 13a is pivotally connected by the pin 13c and by the pin 13b between the plunger 13 and the lever 14b as shown best in Fig. 7 of the drawings. This lever 14b is in connection with the gate 14a of the valve 14. Positioned over one end of this lever 14b is the weight 14c which weight may be shifted therealong and secured in any position desired by means of the bolt 14d. In Fig. 7 of the drawings this gate 14a of the valve 14 is shown open. To close the valve the plunger 13 must be drawn up into the solenoid 11 by means of the magnetic field created by an electric current flowing through the windings of this solenoid 11. When the current ceases to flow through the windings of this solenoid 11, the gate 14a will open due to the dropping due to gravity, of both the plunger 13, the lever 14b, and its weight 14c. When the gate 14a of the valve 14 thus opens, the fluid within the cylinder 1 is thus permitted to flow back to the reservoir R. The solenoid 11 is controlled from the elevator.

When the piston 2a has reached the end of 75

the cylinder 1 having the cap 1a, the motor 18 driving pump 17 will stop, as will be described hereinafter. A pressure relief valve 16 is provided to return the hydraulic fluid to the reservoir R directly from pump 17. This valve 16 connects with the pump 17 through pipes 16a and 17b and connects with the reservoir R through pipe 16b and 17d. The check valve 15 prevents the hydraulic fluid within the cylinder 1 from returning through the pipe 15a, and this hydraulic fluid, once it has been pumped into the cylinder 1, will not be returned therefrom until valve 14 opens. When this valve 14 does open, the hydraulic fluid within the cylinder 1 will be displaced therefrom by the piston 2a returning from the end of the cylinder 1 having cap member 1a to the end of the cylinder having cap member 1b. The piston 2a will be returned to the end of the cylinder 1 having the cap 1b thus displacing hydraulic fluid within the cylinder 1 out through valve 14 back to reservoir R by the action of the weight 1c acting on the lever arm 1b of the valve gate lever 7, the lever arm 7a of this lever 7 acting on the crosshead 3, and the crosshead 3 acting on the piston 2a to the piston rod 2. It should be noted that as this hydraulic fluid is thus being discharged from the piston 1, that the gate G of the valve A is being closed, and that this cannot happen until the gate 14a of the valve 14 opens and further that the opening of the gate 14a of the valve 14 is controlled by the solenoid 11 which in turn is controlled through an electric circuit, not shown, used in connection with the elevator. When the gate G of the valve A does close, the elevator must necessarily come to a stop since when this gate G is closed the hydraulic fluid can neither be pumped to the cylinder of this elevator, nor can the hydraulic fluid be returned from the cylinder of the elevator, since to do so the fluid must pass through the pipe P and through the valve A past the gate G thereof.

The piston 2a on its discharge stroke along with the crosshead 3 and the gate G of the valve A, as said gate G is being closed by the action of the weight 1c and the lever 1b, will be stopped at a predetermined point before the gate G is completely closed. The crosshead 3 in moving with the piston 2a on its discharge stroke along the guide 4 will be arrested by the knuckle member 5. This member 5 is pivotally secured to the face of the channel member C by the bolt 5a and rests upon stud 5i and set screw 5g, which set screw is secured to the crosshead guide 4, all as shown best in Figs. 2 and 4 of the drawings and to some extent in Fig. 5. This set screw 5g is provided with the adjustment nut 5h. The knuckle member 5 is provided with a bifurcated portion, which is composed of the arms 5b and 5c as indicated in Fig. 5, the one end of which bifurcated member is secured by the bolt 5a to the channel C and the bifurcated ends composed of the arms 5b and 5c of which is provided with the pin 5d extending therethrough and securing the member 5e between the arms 5b and 5c thereof. The member 5e has secured in its one end the bolt 5f. This member 5 normally rests upon the head of the set screw 5g and the stud 5i. This stud 5i is secured to the guide member 4 as indicated best in Fig. 2 of the drawings. When this knuckle member 5 is resting upon the stud 5i and the set screw 5g, a line drawn through the head of the bolt 5f, the center of the pin 5d and the center of the head of bolt 5a would be a straight line and would lie in a horizontal plane.

The crosshead 3, in moving with the piston 2a on its discharge stroke, will be arrested by the head of the bolt 5f of the knuckle member 5 coming into contact with the recess 3e and the shoulder 3f of the crosshead 3. This piston 2a as well as crosshead 3 and valve gate G will be thus stopped until the knuckle is tripped so as to permit the crosshead 3 along with the piston 2a and the gate G to complete its travel. The knuckle 5 will be tripped by the stud 6e of the trip member 6 lifting up against the under side of the bifurcated arms 5b and 5c as indicated in Figs. 2 and 5 of the drawings.

The trip member 6 is pivotally secured to the guide member 4 by the pin 6d as shown best in Figs. 2, 4, and 5 of the drawings. This trip member 6 has the arm 6a, to the upper end of which is pivotally secured the rod 12a of the solenoid plunger 12. The other arm 6b of this trip member 6 has secured to its end the weight 6c. This trip member 6 also has the stud 6e. The normal position for the trip member 6 is shown by dotted outline in Fig. 2 of the drawings. When in this position the knuckle member 5 is resting upon the stud 5i and upon the head of the set screw 5g. This trip member 6 is held in this position by the magnetic field created by the solenoid 10 acting upon the solenoid plunger 12. This plunger 12 is connected with the lever 12b through the link 12c which lever is pivotally connected by its one end to the pin 12c against the side of the channel member C. Integral with the lever 12d is the lever 12b which in turn is connected by its one end to the rod 12a. The levers 12b and 12d move as a unit about the pin 12c whenever the solenoid plunger 12 is moved, and in this fashion move the rod 12a. As long as the solenoid 10 is energized, the plunger 12 will hold the trip member 6 in the position shown for it by dotted outline in Fig. 2 of the drawings. But when this solenoid 10 is no longer energized, the plunger 12 may drop to the position shown for it in Fig. 1 of the drawings, thus allowing the trip member 6 to shift to the position shown for it by solid outline in Figs. 1 and 2 of the drawings. The stop member 6f contacts arm 6a to prevent trip 6 from moving beyond the position shown for it by solid outline in Fig. 2 when plunger 12 drops. The weight 6c on the lever 6b aids in shifting the trip member 6 when plunger 12 drops, and the trip member 6 in pivoting about the pin 6d will lift the knuckle member 5 to the position shown for it by solid outline in Fig. 2 of the drawings by means of the stud 6e. When the knuckle member 5 has been tripped to the position shown for it by solid outline in Fig. 2, the crosshead 3, the piston 2a and the gate G of the valve A may complete their travel, so that the gate G of the valve A may close completely and so that the piston 2a of the moment when the solenoid 10 will cease to be energized so that the knuckle member 5 may be broken, as hereinbefore described, is determined by a means not shown nor described in either the specification or the drawings, but occurs shortly before the moment the elevator is to stop in either its ascent or its descent.

The pump 17 and the motor 18 are not in operation when the gate G of the valve A is completely open. The motor 18 shown in Fig. 9 of the drawings is a three-phase motor, although a single phase motor could be used equally as well. The electrical energy is supplied to this motor 18 by the wires running through the conduit 18c, there being three such wires. Two of

these wires have the terminal members 18d and 18e which make contact with the switch 19b of the solenoid plunger 19a of the solenoid 19. Hence, when this switch member 19b makes contact with the two terminals 18d and 18e, electrical energy will be furnished to the motor 18, but this switch member 19b will make contact with the elements 18d and 18e only when the solenoid 19 is energized. When the solenoid 19 winding 19 is no longer energized, the plunger 19a along with the switch 19b will fall away from the elements 18d and 18e, thus interrupting the flow of electrical energy to the motor 18. In the circuit with the solenoid 19 is the mercury switch 8. One side of the solenoid 19 connects with the conductor 19e, the other side of this solenoid 19 connects with the conductor 19c. This conductor 19c connects with the mercury switch 8, and another conductor 19f connects with the mercury switch 8 as indicated in Figs. 1 and 9 of the drawings. This mercury switch 8 is a glass tube 8e closed at its end containing the mercury 8b as shown best in Fig. 8 of the drawings. Two terminal members 8c extend part way into the tube 8e through one closed end thereof as indicated in Fig. 9 of the drawings. One terminal 8c connects with the conductor 19c and the other terminal 8c connects with the conductor 19f. The conductors 19e and 19f connect with a source of electrical energy which is not shown in the drawings. Hence, when the glass tube 8e of the mercury switch 8 is held in the position such that the mercury 8b will run down into the end supporting the elements 8c, electrical connection between said elements 8c is thusly made. By rotating the position of this glass tube 8e so that the mercury 8b will run away from the end having the elements 8c, electrical connection is thusly broken. The glass tube 8e is supported within a clip 8d, which clip 8d is secured to the circular plate 8f and both the plate 8f and the glass tube 8e pivot about the pin 8g. The pin 8g is secured to one side of the casing 8h and the glass tube 8e, the clip 8d, the circular plate 8f are all positioned within this casing 8h. Between the circular plate 8f and the side of the casing 8h and secured by its one end to the pin 8g is the link member 8i. This link member 8i connects by its other end to one end of the rod 8a as shown best in Fig. 1 of the drawings. The end of the link 8i connecting with the rod 8a is positioned within the recess 8j which recess is cut in the periphery of the circular plate 8f. Thus when the rod 8a shifts laterally, the circular plate 8f rotates about the pivot 8g. This rod 8a being connected to the mercury switch trip member is caused to shift laterally thereby. This trip member 9 has the arm 9a which connects with the rod 8a and also has the bifurcated portion 9b, and is secured upon the pin 9c to the side of the channel member C, all as shown best in Fig. 1 of the drawings. The trip member 9 is caused to shift by the stud 3k of the crosshead member 3 contacting either of the arms of the bifurcated portion 9b. For the position shown for the switch in Figs. 1, 8, and 9 of the drawings, the motor 18 is running and will continue to run and drive the pump 17 until the trip member 9 is shifted by the stud 3k of the crosshead 3 causing the mercury switch 8 to rotate to a position where the mercury 8b will run away from the elements 8c in the glass tube 8e, thus breaking the circuit for the solenoid 19 and consequently allowing the switch 19b to move away from the contact elements 18d and 18e.

The rod 8k is secured by its one end to the circular plate 8f near the periphery of said circular plate. The other end of the rod 8k extends through the slot 8p in the casing 8h. The spring 8m is secured over the rod 8k between the upper edge of the casing 8h and the periphery of the circular plate 8f as shown best in Figs. 1 and 8 of the drawings. This spring 8m and the rod 8k serve to hold the circular plate 8f in its extreme positions as shown best in Fig. 1 of the drawings. However, a failure of the spring 8m would not render the apparatus inoperative inasmuch as the mercury switch 8 would still move in response to a movement of trip 9.

The solenoids 10 and 11 are secured within the casing 21, and this casing 21 is positioned across the end of the automatic hydraulic elevator valve control as shown best in Fig. 6 of the drawings. The casing 21 is provided with a panel 20, which panel 20 is of some non-conductive material such as "bakelite" and has secured through it a plurality of terminal members 20a. These terminal members connect with the mercury switch 8, with the solenoids 10 and 11 and with the electric motor 18.

The operation of my automatic hydraulic elevator valve control is substantially as follows:

When the elevator is not in use the gate G of the valve A is closed. When the elevator is called into use the gate G of the valve A must be opened, and this is accomplished by pumping hydraulic fluid into the cylinder 1 so as to force the piston 2a to travel from the end of the cylinder 1 having the cap member 1b to the end having the cap member 1a. As the piston 2a thus moves through its strokes, it carries with it the crosshead 3 because of its connection with the piston rod 2 and also causes the gate G of the valve A to pivot about the journal B thereof because of the connection of the crosshead 3 with the arm 7a of the valve gate lever 7 and the crosshead link 3a. The pump 17 and the motor 18 which drives this pump are called into operation when the solenoid 10 is energized, thus causing the switch 19b to make contact with the elements 18d and 18e, thus furnishing electrical energy to the motor 18. At this time the mercury switch 8 is in a position such that the mercury 8b in the glass tube 8e makes contact between the elements 8c, which elements 8c connect with the conductors 19c and 19f. The hydraulic fluid is pumped by the pump 17 from the reservoir R through the pipe 17d to the pipe 17c to the pump 17 and from the pump 17 to the check valve 15 through the pipe 17b and 16a and from the check valve 15 to the cylinder 1 through the pipes 15a and 1d. During all this time the valve 14 has remained closed. When the piston 2a reaches the end of the cylinder 1, having the cap 1a, the gate G of valve A will be open and the stud 3k of the crosshead 3 will contact one of the arms of the bifurcated portion 9b of the mercury switch trip member 9 causing the same to rotate the glass tube 8e of the mercury switch 8 to a position such that the mercury 8b in this tube 8e will run away from the end of the tube 8e having the element 8c, thus breaking the electrical circuit to the solenoid 10. When this happens the switch 19b will move away from the contact member 18d and 18e thus cutting off the supply of electrical energy to the motor 18. In this manner the pump 17 is shut off automatically and remains shut off while gate G of valve A is open full until the mercury switch 8 is tripped back to its original position where the mercury 8b will again make

contact between the element 8c. This will not happen until after the piston 2a and the crosshead 3 start to return to their original positions; that is, until the piston 2a starts to move away from the end of the cylinder having the cap 1a towards the end of the cylinder having the cap 1b, but the piston 2a cannot make this return stroke until the hydraulic fluid within the cylinder 1 is released therefrom, and this is accomplished by opening the valve 14. The gate 14a of this valve 14 is operated by the plunger 13 of the solenoid 11 and will open when the solenoid 11 ceases to be energized electrically. The lever 14b and the weight 14c along with the weight of the plunger 13 acting on the lever 14b due to the action of gravity will cause this gate 14a of the valve 14 to open, and conversely when the solenoid 11 is energized, the plunger 13 will be lifted up into this solenoid 11 so as to close the gate 14a of the valve 14. Hence, to open the valve 14 to permit the hydraulic fluid within the cylinder 1 to return to the reservoir R, the gate 14a of the valve 14 must be opened and this happens when the circuit for the solenoid 11 is broken. The time when this circuit is broken is a predetermined matter which depends upon the level of elevation where the elevator is to be stopped. The hydraulic fluid returns from the cylinder 1 through the pipe 1d and 14f through the valve 14 to the pipe 14e and 17b and back to the reservoir R. As this fluid is being discharged from the cylinder 1, the piston 2a and the crosshead 3 are being returned to their original positions by the action of the weight 7c on the end of the lever arm 7b, and as this is happening, the gate G of the valve A is being closed; but before the crosshead 3 and the piston 2 are completely returned to their original position, the crosshead 3 is arrested by contacting the knuckle member 5. When this happens the crosshead 3 and the piston 2a cease moving, thus leaving the gate G of the valve A still slightly open and permitting the elevator to slowly creep to the desired level. The valve 14 during this time remains open. The piston 2a and the crosshead 3 may not complete their return stroke until the knuckle member 5 is tripped by the stud 6e of the trip member 6. This trip member 6 is connected with the plunger 12 of the solenoid 10 by means of the rod 12a, the levers 12b and 12d and the link member 12e. This trip member 6 is normally held in the position shown for it by dotted outline in Fig. 2 of the drawings by the plunger 12 being drawn up into the solenoid 10, the plunger 12 being attracted by the magnetic field created by the electric current flowing through this solenoid 10. This plunger 12 will remain in this position until the electric current ceases to flow through the solenoid 10. The electric current flowing through this solenoid 10 is cut off shortly before the elevator reaches its desired level of elevation. The time interval between the cutting off of the current flowing through the solenoid 10 and the complete closure of the gate G of the valve A so that the elevator comes to a complete stop is approximately one second, but this may be varied by shifting weight 7c along arm 7b. When this electric current ceases to flow through the solenoid 10, the plunger 12 will drop due to action of gravity. Also the trip member 6, because of the weights 6c on the lever arm 6b thereof, will pivot about the point 6d so that the stud 6e will lift up against the under side of the knuckle member 5, shifting the same to the position shown for it by solid outline in Fig. 2 of

the drawings and thus permitting the crosshead 3 and the piston 2a to complete their return stroke and also permitting the gate G of the valve A to close completely. In this manner the formation of a hydraulic hammer is avoided and also the operation of the elevator is greatly improved by the elimination of any sudden stoppage. Furthermore, in this manner the elevator can be automatically stopped at any predetermined elevation desired in an automatic manner and entirely independent of the loading on said elevator.

It should be noted that in the event the source of electrical energy to the motor 18 and to the solenoids 10, 11, and 19 should fail, the elevator will stop immediately, since both the plungers 12 and 13 of the solenoids 10 and 11 respectively would be permitted to drop, thus opening the valve 14 and also tripping the knuckle 5 as hereinbefore described.

Though I have shown and described a particular construction, combination, and arrangement of parts and portions, I do not wish to be limited to this particular construction, combination, and arrangement, but desire to include in the scope of my invention the construction, combination, and arrangement substantially as set forth in the appended claims.

Having thus described my invention, what I claim as new and desire to secure by Letters Patent is:

1. In an automatic hydraulic elevator valve control of the class described, the combination of a cylinder, a piston reciprocally mounted therein, a crosshead member in connection with said piston, guide means in connection with said crosshead member, a means to stop said crosshead member in its movement at a predetermined point and a trip means for said crosshead member stop means.

2. In an automatic hydraulic elevator valve control of the class described, the combination of a cylinder, a piston reciprocally mounted therein, a piston rod connected with said piston, a crosshead secured to said piston rod, a guide member supporting said crosshead, a link member connected to said crosshead, a lever pivotally and adjustably connected with said link member, and a weight adjustably mounted on said lever and a knuckle member connected with said crosshead arranged to stop said crosshead on its re-

turn stroke.

3. In an automatic hydraulic elevator valve control of the class described, the combination of a cylinder, a piston reciprocally mounted therein, a piston rod connected with said piston, a crosshead secured to said piston rod, a guide member supporting said crosshead, a link member connected to said crosshead, a lever pivotally and adjustably connected with said link member, a weight adjustably mounted on said lever, a knuckle member connected with said crosshead arranged to stop said crosshead on its return stroke, and a trip member positioned to engage said knuckle member and trip the same.

4. In an automatic hydraulic elevator valve control of the class described, the combination of a cylinder, a piston reciprocally mounted therein, a piston rod connected with said piston, a crosshead secured to said piston rod, a guide member supporting said crosshead, a link member connected to said crosshead, a lever pivotally and adjustably connected with said link member, a weight adjustably mounted on said lever, a knuckle member connected with said crosshead arranged to stop said crosshead on its return stroke, a trip member positioned to engage said knuckle member and trip the same, and a solenoid provided with a plunger reciprocally mounted therein in connection with said trip member.

5. In an automatic hydraulic elevator valve control of the class described, the combination of a cylinder, a piston reciprocally mounted therein, a piston rod connected with said piston, a crosshead secured to said piston rod, a guide member supporting said crosshead, a link member connected to said crosshead, a lever pivotally and adjustably connected with said link member, a weight adjustably mounted on said lever, a knuckle member connected with said crosshead arranged to stop said crosshead on its return stroke, a trip member positioned to engage said knuckle member and trip the same, a solenoid provided with a plunger reciprocally mounted therein in connection with said trip member, the solenoid operated by its magnetic field to hold its plunger within its core and to hold said trip member out of engagement with said knuckle member for a predetermined time.
